CLAIM

The ornamental design for a transformable desk lamp with 3 light bars, as shown and described.

DESCRIPTION

FIG. 1 is a top perspective view of a transformable desk lamp with 3 light bars, showing my new design.

FIG. 2 is a front view of a transformable desk lamp with 3 light bars.

FIG. 3 is a rear view of a transformable desk lamp with 3 light bars.

FIG. 4 is a left side view of a transformable desk lamp with 3 light bars.

FIG. 5 is a right side view of a transformable desk lamp with 3 light bars.

FIG. 6 is a top view of a transformable desk lamp with 3 light bars.

FIG. 7 is a bottom view of a transformable desk lamp with 3 light bars.

FIG. 8 is a perspective view thereof, showing the transformable desk lamp with 3 light bars in state of use.

FIG. 9 is a bottom perspective view of a transformable desk lamp with 3 light bars.

FIG. 10 is an enlarged view of a transformable desk lamp with 3 light bars taken from the circle part in FIG. 2.

FIG. 11 is an enlarged view of a transformable desk lamp with 3 light bars taken from the circle part in FIG. 3; and, FIG. 12 is an enlarged view of a transformable desk lamp with 3 light bars taken from the circle part in FIG. 6.

The broken lines in the drawings depict portions of the transformable desk lamp with 3 light bars that form no part of the claimed design.

1 Claim, 12 Drawing Sheets
